UNITED STATES PATENT OFFICE.

HANS KÜHNE, OF LEVERKUSEN, AND FRANZ BENCKER, OF MULHEIM, NEAR COLOGNE, GERMANY, ASSIGNEES TO FARBENFABRIKEN VORM. FRIEDR. BAYER AND CO., OF LEVERKUSEN, NEAR COLOGNE, GERMANY.

MANUFACTURE OF HYPOSULPHITES.

Application filed November 18, 1921. Serial No. 516,139.

To all whom it may concern:

Be it known that we, HANS KÜHNE and FRANZ BENCKER, citizens of Germany, residing at, respectively, Leverkusen and Mulheim, near Cologne, Prussia, Germany, have invented new and useful Improvements in the Manufacture of Hyposulphites, of which the following is a specification.

It is known that hyposulphites can be obtained by causing sodium amalgam to react with an aqueous solution of a bisulfite (acid sulfite).

This method however is not economical as a small yield only is obtained.

According to this invention highly concentrated hyposulphite (salts of the hyposulfurous acid $H_2S_2O_4$) are obtained by treating a solution of a bisulfite ($NaHSO_3$, etc.) with an amalgam preferably that of an alkali metal and with a free acid HCl , H_2SO_4 , SO_2 for example. The best results are obtained if the acid is present in such quantity as is equivalent to the non-mercurial metal of the amalgam.

In carrying out the invention the bisulfite solution is well cooled and stirred, the amalgam and acid being added in proportionate quantities either in batches or continuously.

Preferably the amalgam is obtained electrolytically, the mercury subsequently set free by the reaction being returned to the electrolytic cell.

The accompanying drawing illustrates one form of apparatus suitable for carrying out the invention.

Example.—A caustic soda or sodium chlorid solution is electrolyzed in an electrolytic cell A, provided with an anode B of nickel and a cathode C of mercury. The sodium amalgam thus produced is then removed from the cell through a siphon D and run into a closed vessel E containing bisulfite solution ($NaHSO_3$). The mixture is cooled and well stirred with the amalgam by the operation of the agitator K, care being taken to exclude air. The mercury set free is run from the vessel E through a siphon F to a pump G, which delivers it back to the electrolytic cell A. A free acid, H_2SO_4 for example is added simultaneously with the

amalgam to the bisulfite through the pipe L in a quantity in proportion to the current in the cell. The solution of hyposulphite thus obtained is then treated in the known manner.

The acid employed must of course be one which is of such a nature that it will not destroy the hyposulphite product under the operating conditions. For example, the acid must be one which will not oxidize the hyposulphite product. In some of the appended claims the expression "non oxidizing acid" is employed for the purpose of excluding the use of such acids.

This indirect electrolytic process has a great advantage over the hitherto known direct electrolytic process in that firstly troublesome diaphragms are avoided, secondly the apparatus required is more simple as the electrolytic apparatus need not be air tight and thirdly secondary reactions are avoided and also the reduction is more easily prevented from proceeding too far.

Having now particularly described and ascertained the nature of our said invention and in what manner the same is to be performed, we declare that what we claim is:

1. A process for the manufacture of hyposulphites which consists in treating a solution of a bisulfite with an amalgam and a free non-oxidizing acid, substantially as described.

2. A process for the manufacture of hyposulphites which consists in treating a solution of a bisulfite with an amalgam and a free non-oxidizing acid in quantity chemically equivalent to the non-mercurial metal of the amalgam.

3. Process for the manufacture of hyposulphites as defined in claim 1 in which H_2SO_4 is the free acid employed.

4. Process for the manufacture of hyposulphites as defined in claim 2 in which H_2SO_4 is the free acid employed.

5. A cyclical process for the manufacture of hyposulphites which consists in forming an amalgam electrolytically leading the amalgam into a solution of a bisulfite, causing the reaction between the amalgam and the bisulfite to take place in the presence of 100

a free non-oxidizing acid and returning the mercury set free into the electrolytic cell. set our hands in the presence of two subscribing witnesses.

6. A cyclical process for the manufacture of hyposulphites as defined in claim 5 in which H_2SO_3 is the free acid employed in quantity equivalent to the non-mercurial element of the amalgam.

In testimony whereof we have hereunto

HANS KÜHNE. [L.S.]
FRANZ BENCKER. [L.S.]
